(57) **CLAIM**

(***) Term: **14 Years**

We claim the ornamental design for a combined compact tractor operator platform, hood and fuel tank, as shown and described.

(21) Appl. No.: **29/115,965**

DESCRIPTION

(22) Filed: **Dec. 23, 1999**

FIG. 1 is a front left corner perspective view of the combined compact tractor operator platform, hood and fuel tank in relationship to the unclaimed compact tractor.

(51) LOC (7) Cl. **15-03**

FIG. 2 is a side perspective view as seen from the left side showing the combined compact tractor operator platform, hood and fuel tank in relationship to the unclaimed compact tractor.

(52) U.S. Cl. **D15/23; D15/31**

FIG. 3 is a front perspective view of the combined compact tractor operator platform, hood and fuel tank in relationship to the unclaimed compact tractor.

(58) Field of Search D15/10, 15, 17,

FIG. 4 is a rear right corner perspective view of the combined compact tractor operator platform, hood and fuel tank in relationship to the unclaimed compact tractor; and,

D15/22-26, 28, 30, 31, 33; D12/164, 165;
56/17.5, 202, 255, 294, 320.1, 320.2; 172/811;
180/69.2, 89.1, 89.12, 89.13

FIG. 5 is a rear perspective view of the combined compact tractor operator platform, hood and fuel tank in relationship to the unclaimed compact tractor.
